UNITED STATES PATENT OFFICE

ALBERT H. QUAST AND OSCAR B. OLSEN, OF CHICAGO, ILLINOIS

DESIGN FOR A WEDDING RING

Application filed March 15, 1930. Serial No. 34,903. Term of patent 3½ years.

To all whom it may concern:

Be it known that we, ALBERT H. QUAST and OSCAR B. OLSEN, citizens of the United States, residing at Chicago, in the county of Cook and State of Illinois, have invented a new, original, and ornamental Design for Wedding Rings, of which the following is a specification, reference being had to the accompanying drawing, forming part thereof.

The figure of the drawing is a perspective view of a wedding ring showing our new design, the detailed illustration being continued throughout the circumference of the ring as indicated by the dot and dash lines.

We claim:

The ornamental design for a wedding ring, as shown and described.

ALBERT H. QUAST.
OSCAR B. OLSEN.
